UNITED STATES PATENT OFFICE.

WILLIAM TIFFANY, OF CRESWELL, OREGON.

RAILROAD PUMP-MOTOR.

SPECIFICATION forming part of Letters Patent No. 375,024, dated December 20, 1887.

Application filed October 6, 1887. Serial No. 251,648. (No model.)

To all whom it may concern:

Be it known that I, WILLIAM TIFFANY, a citizen of the United States, residing at Creswell, in the county of Lane and State of Oregon, have invented a new and useful Improvement 5 in Railroad Pump-Motors, of which the following is a specification.

My invention relates to an improvement in railroad pump-motors; and it consists in the 10 peculiar construction and combination of devices, that will be more fully set forth herein-after, and particularly pointed out in the claims.

In the drawings, Figure 1 is a top plan view 15 of a railroad pump-motor embodying my improvements. Fig. 2 is a side elevation of the same. Fig. 3 is a vertical transverse sectional view taken on the line $x-x$ of Fig. 1. Fig. 4 is a detail perspective view showing one of the 20 connections between the cam-levers and the rock-shafts.

A represents the rails of a railway-track of the ordinary construction, supported upon cross-ties B.

C represents a cross-bar, of wood or other 25 suitable material, which is arranged transversely under the track between two of the ties B, and on the upper side of the said bar is secured a tie-yoke, D, which is made of metal, 30 extends under the lower sides of the track-rail, and has its ends bent upward at right angles to form vertical arms E, which are arranged at slight distances beyond the outer sides of the track-rails. The upper ends of 35 these arms E are slightly lower than the level of the tops of the track-rails.

F represents a pair of levers, which are arranged longitudinally on the outer sides of the track-rails and bear between the inner sides of 40 the arms E and the outer sides of blocks G, which blocks are secured on the outer sides of the rails. Bolts H extend transversely through the rails A, the blocks G, and the centers of the levers F, and through openings near the 45 upper ends of the vertical arms E, the said bolts serving to connect the rails, the blocks, the levers, and the arms firmly together, and also forming the pivots or fulcrums on which the levers F turn. The function of the tie-yoke is to prevent the rails from spreading 50 apart.

The upper sides of the levers F, at opposite ends thereof, are curved, as shown in Fig. 2, and thereby form double cams I. The said cams extend a slight distance above the tops 55 of the rails, and are thereby adapted to be engaged by the treads of the wheels of passing trains. The ends of the levers F are turned downward, as at K, and are bifurcated to form ears L.

M represents a pair of rock-shafts, which extend transversely under the track-rails and are journaled in suitable bearings, N, the said rock-shafts being arranged at slight distances beyond the ends of the levers F. Each of the 65 said rock-shafts is provided with a pair of inward-extending arms, O, which are connected to the adjacent ends of the levers F by means of links P. To one end of each rock-shaft is attached a cross-bar or lever, R, by means of 70 a set-screw, S. The said cross-bars or levers are adapted to be attached to the rods of the pumps which are to be operated by the motor.

The operation of my invention is as follows: The machine is in its normal position when 75 the levers F and the levers R are arranged horizontally, with the cams I on the upper sides of the levers F, slightly above the tops of the track-rails. When a train passes along the track, each of its wheels engages alternately 80 with the cams I at each end of the levers F, and thereby causes the said levers F to rock or oscillate in a vertical plane and transmit their motion to the rock-shafts M, and consequently impart rocking or oscillating motion 85 to the cross-bars or levers R, and thereby reciprocate the plungers of the pumps. When it is desired that a train shall pass without operating the pump, this may be accomplished by loosening the screws S, so that the shafts 90 M may rock without imparting motion to the bars or levers R.

I do not limit myself to the use of this motor in connection with pumps, as it is evident that it may be employed to operate other 95 mechanism.

Having thus described my invention, I claim—

1. The combination, with the track, of the 100 rocking levers F, having the cams I, adapted to be engaged by the wheels of a passing train, and the rock-shafts M, connected to the levers

F, for the purpose set forth, substantially as described.

2. The combination, with the track-rails, of the rocking levers F, having the cams I at opposite ends, the rock-shafts M, having the arms N, and the links O, connecting said arms to the cam-levers, substantially as described.

3. The combination, with the track-rails, of the tie-yoke arranged under the same and having the vertical arms E, the double-cam levers F, arranged between the said vertical arms and the track-rails, and the bolts passing transversely through the track-rails, the cam-levers, and the arms E, for the purpose set forth, substantially as described.

4. The combination, with the track-rails A,

of the double-cam levers F, adapted to be operated by the wheels of passing trains, the rock-shafts M, having the arms N, the links O, connecting the said arms to the adjacent ends 20 of the cam-levers, the cross-bars or levers R, fitted on the rock-shafts, and the set-screws S, to clamp the said cross-bars or levers to the said rock-shafts, substantially as described.

In testimony that I claim the foregoing as 25 my own I have hereto affixed my signature in presence of two witnesses.

WILLIAM TIFFANY.
